FIGURE TOY

Jasper Likes, Long Beach, Calif.

Application March 4, 1936, Serial No. 67,144

5 Claims. (Cl. 46—105)

This invention relates to toys and its general object is to provide a figure toy of the handle supported, propelled type which is in the form of a comical figure including a body of spherical formation rotatably mounted and engageable with the ground, with leg and feet members carried by and acting to rotatably mount the spherical body with respect to the remaining portion of the toy so that when the toy is pushed or propelled along the ground, the spherical body will rotate and move the leg and feet members accordingly to simulate walking, thereby creating a comical appearance to bring about fun and amusement.

15 A further object of the invention is to provide a toy of the character set forth, that is simple in construction, inexpensive to manufacture, easy to operate and extremely efficient in operation and service.

20 This invention also consists in certain other features of construction and in the combination and arrangement of the several parts, to be hereinafter fully described, illustrated in the accompanying drawing and specifically pointed out in 25 the appended claims.

In describing the invention in detail, reference will be had to the accompanying drawing wherein like characters denote like or corresponding parts throughout the several views, and 30 in which:

Figure 1 is a perspective view of the toy which forms the subject matter of the present invention.

Figure 2 is a vertical sectional view taken therethrough, with parts in elevation.

35 Referring to the drawing in detail, the reference numeral 1 indicates the body of the toy, which in the form as shown is solid and spherical in form. However, the body may be oval, or any other shape suitable for the purpose.

40 Disposed about the upper portion of the body and substantially fitting the same, but spaced therefrom, is a hollow hemispherical shell 2 having diametrically opposed openings adjacent its lower edge for the passage of crank shafts 3 therethrough, for disposal into the body, for mounting the shell thereon. The crank shafts are embedded in the body and the embedded portions preferably have spurs or barbs 4 extending therefrom, to prevent casual removal or displacement of the shafts.

45 The crank portions 5 of the shafts are bent in opposed directions to terminate at right angles with respect to the embedded portions thereof,

and secured to the outer ends of the crank portions are members 6 shaped to simulate shoes, arranged above the ground, so as to not contact the same when the toy is in use.

Secured to the shell at the extreme upper end 5 thereof, through the medium of a pin or the like 7, is a head 8, and the pin also acts to secure a flexible element 9 between the head and shell due to the fact that the pin extends through the flexible element midway its ends. The head 10 may have a groove extending across its lower side to receive the flexible element which in fact is a cord or the like, and extends upon opposite sides of the head to simulate arms, with knobs 10 secured to the ends thereof.

15 The head is painted or otherwise decorated to simulate a face, and pins 11 are secured and rise from the upper surface of the head in the form as shown, to cooperate with the spindly arms and legs and the spherical body to give the 20 appearance of a grotesque figure in the form of a bug. However, the toy may be made in various shapes and forms, to simulate a duck, a human being, or anything having a short, round figure.

25 The shell is painted or otherwise decorated to simulate a coat and I have likewise shown a tie, but in any event the shell has secured thereto and rising therefrom a rod like handle 12 by which the toy is propelled by being pushed or pulled, as will be apparent.

30 It will be obvious that the body 1 is disposed in contact with the ground and as the shell is held in an upright position through the instrumentality of the handle, and the toy propelled along the ground, the body will rotate and cause the crank shafts to move accordingly therewith, to simulate walking. Due to the flexibility of the element 9, it will be further obvious that the arm portions will have a tendency to wave, with the result the toy will have 40 a life like appearance.

35 It is thought from the foregoing description that the advantages and novel features of the invention will be readily apparent.

45 It is to be understood that changes may be made in the construction and in the combination and arrangement of the several parts, provided that such changes fall within the scope of the appended claims.

50 What I claim is:

1. A toy comprising a ground engaging body, a shell disposed about the body, leg members connecting the shell with the body, arm and head members secured to the shell, and a handle secured to and extending from the shell for 55

- rolling the body along the ground to rotate the same and the leg members accordingly.
2. A figure toy comprising a ground engaging body of rounded formation, a shell disposed about the body, leg members extending through the shell and into the body to be secured thereto and for securing the shell accordingly, members secured to the outer ends of the leg members to simulate shoes spaced above the lower end of the body, a head secured to the shell, flexible arms extending from the shell, and a handle fixed to the shell for propelling the body along the ground for rotating the same and the legs respectively.
3. A figure toy comprising a spherical body, a hemispherical shell disposed about the body, crank shafts including portions passing through the shell and embedded in the body for connecting the shell thereto, said crank shafts being bent to provide leg portions terminating at right angles to the embedded portions, members secured to the leg portions and simulating shoes spaced above the lower end of the body, a head secured to the shell, flexible means secured to the shell below the head and simulating arms, knobs secured to the ends of the flexible means, and a rod like handle fixed to the shell for rolling the body along the ground in propelling the toy.
4. A figure toy comprising a spherical body adapted to contact the ground, a hemispherical shell disposed about the body in spaced fitting association therewith, crank shafts including portions passing through the shell upon diametrically opposite sides thereof and embedded in the body for connecting the shell therewith, legs provided by the crank portions of the shafts, members secured to the outer ends of the legs to simulate shoes spaced from the lower end of the body, a head connected to the shell, a flexible element secured to the shell between the latter and the head respectively to project outwardly therefrom to simulate arms, and a rod like handle secured to and extending rearwardly from the shell for propelling the toy with the body disposed to roll along the ground to rotate the same, and the legs respectively.
5. A figure toy comprising a spherical ground engaging body, a shell disposed about the body and spaced therefrom, crank shafts including portions connecting the shell to the body and embedded in the latter, the crank portions of the shafts simulating legs, means secured to the legs and simulating shoes spaced from the lower end of the body, head and arm members connected to the shell, means for propelling the toy by rolling the body along the ground for rotating the same and legs respectively, and said legs being directed angularly in opposed directions.

JASPER LIKES. 30
